UNITED STATES PATENT OFFICE

165,833

UTILITY DRESSER

Cicero C. Gaither, Birmingham, Ala., assignor of
one-half to R. Glenn Pugh, Birmingham, Ala.

Application January 30, 1951, Serial No. 14,041

Term of patent 14 years

(Cl. D33—19)

To all whom it may concern:

Be it known that I, Cicero C. Gaither, a citizen of the United States of America, residing at Birmingham, county of Jefferson, and State of Alabama, have invented a new, original, and ornamental Design for a Utility Dresser, of which the following is a specification, reference being had to the accompanying drawing, forming a part thereof, wherein:

Figure 1 is a perspective view of a utility dresser with its upper doors closed and its lower doors opened, and with the slide in extended position, showing my new design, and

Figure 2 is a similar view of the same with all doors closed.

I claim:

The ornamental design for a utility dresser, as shown.

CICERO C. GAITHER.
